UNITED STATES PATENT OFFICE

2,518,964

PORTABLE SELF-PROPELLED EXCAVATOR

Fred L. White, Marion, Ohio, assignor to The Osgood Company, Marion, Ohio, a corporation of Ohio

Application June 11, 1945, Serial No. 598,806

20 Claims. (Cl. 214—90)

1

This invention relates to material handling devices and in its more specific aspects is directed to an excavator for quickly removing material picked up by the dipper or bucket a considerable distance away from the excavator without swinging the upper body.

One of the objects of this invention is to provide a mechanism on a portable excavator for quickly removing material picked up by the dipper or bucket away from the point of picking up without swinging the excavator dipper away from the point of removal or working face.

Another object of the invention is to provide a conveyor on an excavator for quickly conveying the loosened or removed material away from the excavator dipper without swinging the excavator.

Another object of the invention is to provide a dipper construction on an excavator that will discharge onto a conveyor supported on the excavator for removing the discharged material without swinging the excavator upper body.

Another object of the invention is to provide a conveyor on a portable excavator cooperating with a dipper such that the conveyor will receive material scooped by the dipper for removal to a point remote from the working face.

A still further object of the invention is to provide means on a portable excavator for removing the excavated material to a point remote from the working face without laterally swinging the dipper away from the working face.

Another and a still further object of the invention is to provide a conveyor on a portable excavator which receives material directly from the dipper for removal to a point remote from the working face without laterally swinging the excavator, all driven from a common power source.

Still another object of the invention is to provide an excavator having a conveyor thereon so arranged and organized that it is counter-balanced by the boom and dipper assembly.

Another and still further object of the invention is the provision of a conveyor on an excavator into which the material scooped by the dipper is discharged to remove the material to a point considerably remote from the working face without laterally swinging the excavator upper body or deck.

Other and further objects of the invention will occur to those skilled in the arts to which this invention relates as the description proceeds which taken in connection with the accompanying drawings sets forth a preferred embodiment of the invention but such disclosure is not to be

2

construed as a limitation of the invention which is limited only by the appended claims and any and all modifications, alterations and variations of structure coming within the spirit and scope thereof are deemed to be included herein.

In the drawings:

Fig. 1 shows a general elevational view of an excavator incorporating the invention.

Fig. 2 shows the cable reeving plan.

Fig. 3 is a schematic view of the operating mechanism.

Fig. 4 is a section view taken along the line 4—4 of Fig. 1.

Fig. 5 is a section view taken along the line 5—5 of Fig. 1.

Fig. 6 is an elevational view of a dipper handle attachment.

The disposal of overburden in strip mining or quarrying constitutes such a major problem in the art that various attempts to solve it in the past have proved unsuccessful. The most satisfactory expedient thus far has been the employment of an excavator having a very large dipper enabling the movement of large quantities of overburden during each scooping operation and by means of a long handle made possible the depositing of the material a considerable distance from the excavator. It is also customary to use machines employing long booms with long dipper handles for stripping work in order to deposit the overburden as far as possible from the working face and excavator so as not to interfere with the removal of the uncovered deposit. The swinging of the upper body in a machine of the kind described and the size thereof is a time consuming operation and is one of the principal causes of delay in the rapid removal of overburden and in fact of the rapid handling of material whether useful or not. This invention seeks to increase the material handling ability of an excavator by reducing the lateral swinging movements of the excavator deck or upper body and by means of a suitable conveyor quickly disposing of material scooped up by the dipper or bucket and depositing it at a point remote from the working face, thereby enabling the operator to keep the dipper or bucket adjacent the working face and avoiding the time consuming lateral swinging of the deck or upper body except for positioning the dipper for each successive cut or bite.

The objects and advantages set forth above are achieved in a structure set forth in the accompanying drawings in which 1 designates the chassis and tread mechanism on which the de-

vice is transported over the ground. Rotatably supported thereon in a conventional manner is a deck or upper body structure 2 on which a suitable prime mover 3 is mounted, the prime mover in this instance being an internal combustion engine although an electric motor or any other type of mechanism suitable as a prime mover may be employed.

The prime mover drives a shaft 4 (Fig. 3) which is connected to the prime mover by a power transmitting means 5. Shaft 4 drives a gear system or train 6 for supplying power to the swing and travel mechanism, the latter shown in the transmitting means 7, 8 and 9. The swing mechanism is not shown since it, as well as the travel mechanism, is conventional and well known in the art and a specific disclosure thereof is not essential to the instant invention. Power for travel and swing mechanism is supplied from the shaft 4 through the means of suitable spur and bevel pinions. Shaft 4 has a combination clutch and gear device 13 thereon, which drives a hoist or winch drum 14 by means of a gear and shaft mechanism 15, 16 and 17.

The shaft 4 extends entirely across the machine and while appearing to be in two sections it is in reality a single shaft. For reasons of clarity it is shown divided in order to better disclose other mechanism. The shaft 4 also has a gear and clutch device 19 thereon that drives a winch or hoist drum 23 through a gear and shaft mechanism 21, 22 and 23. The function of the two winding drums 14 and 20 will be subsequently set forth. The mechanism 6 and its components 10, 11, 12, the clutch and gear combinations 13 and 19 associated with shaft 4 are part of the reversing mechanism for the swing and travel mechanism all of which are operated from the single shaft 4.

Gears 17 and 21 are continuously engaged with gears 13' and 19'. This connection requires continuous rotation of the shafts 16 and 22 also making gears 15 and 23 continuously rotatable as well as the drums 14 and 20. The drums are made selectively rotatable by the use of clutches 14'' and 20'' associated with the gears 13' and 19' and when operated in selective conjunction with brakes 14' and 20' enable the complete rotational control of the winding drums. This combination enables the positional control of the mechanisms operatively connected to drums 14 and 20 by means of cables subsequently described.

The shipper shaft for the dipper and its associated handle is driven from the shaft 4 through a gear 23 fixed to the shaft 4 which drives a second gear 24 having a clutch 25 operatively associated with the gear 24 mounted on a shaft 25a to drive a drum or power transmitting support 26. If desired a brake mechanism 27 may be associated with drum or support 26 to hold the dipper in any predetermined position.

Clutch 25 controls the application of power to drum or support 26 and a gear or sprocket 28 secured thereon has a power transmitting element in the form of a gear chain thereabout which drives a cluster sprocket or gear set having wheels 29 and 31 rotatably mounted on a shaft 30. Shaft 30 is also the pivot for the excavator boom. Gear or sprocket 31 has a power transmitting means 32 thereabout which connects with gear 33 fixed to the shipper shaft 34. The control described thus far is a crowd control for urging the dipper into the working face of the material being removed.

Retract means for the shipper shaft 34 is pro-

vided which comprises a clutch and gear combination 35, the gear portion of which meshes with gear 24. The clutch and gear combination 35 is mounted on a suitable shaft 36 on which a gear or sprocket 37 is mounted. A power transmitting means 38 runs about gear 37 and another gear 39 on the drum or support 26. The combination clutch and gear 35 is known as the retract control for withdrawing the dipper from the working face of the material being removed. The clutch and gear combination 35 and the gear and clutch combination 24, 25 constitute a reversible drive mechanism for the shipper shaft 34. Suitable controls for the clutch elements of the combination are provided organized and arranged in a manner such that only one clutch may be closed at one time. These controls are also coordinated with brake 27 whenever the latter is provided.

Shaft 4 has a gear 40 secured to the end thereof which meshes with a gear 41 mounted on a shaft 42. Gear 41 has associated therewith a winch, clutch and brake mechanism 43, 44 and 45 respectively and further associated with the shaft 42 is gear or sprocket 46. Sprocket 46 has a power transmitting means 47 thereabout which drives a gear or sprocket 48 driving conveyor shaft 49. A clutch 50 is operatively associated with the gear or sprocket 46 to control the application of power to conveyor shaft 49. Suitable clutch controls are provided to control the operation of the winch and conveyor drives.

The deck or upper body 2 has suitable brackets 2' thereon to receive rod or shaft 30 on which gear or sprocket cluster 29, 31 is rotatably mounted. The boom 51 is pivotally mounted on the shaft 30 and moves vertically about the shaft as an axis.

Mounted on the deck 2 is bracket or frame 52 in which elements 41, 43, 44, 45, 46 and 50 are mounted. A suitable frame or bracket supports the crowd and retract control previously explained. This support or frame mechanism being conventional in the art no specific frame structure is therefore illustrated.

Supported on the upper body or deck 2 and frame 52 and its complemental frame member is a gantry frame comprising elements 53, 54 and 56. The first mentioned parts are rod or bar members that extend from the edges of deck 2 and up from the approximate center of the deck 2 over the frames 52 is a rod or support 57. Rod 56 braces frame 52 which also absorbs some of the thrust applied by the gantry frame because of the stressing of the bars 53 and 54. Bars 53 and 54 are duplicated on the opposite side of the deck 2 as viewed in Fig. 1 and partially shown in Fig. 2 thereby constituting the gantry frame a rigid support from which the boom 51 and conveyor 58 are suspended.

Conveyor 58 is pivoted to the supporting rod 54 by means of pivot pin 54' which extends through an aperture in an enlarged portion on the rods 54, the conveyor having bosses or brackets 58' suitably apertured through which pivot pin 54' extends. The bosses or brackets 58', only one of which is shown, are disposed in axial alignment, one on each side of the conveyor and are arranged as close to the lower end of the conveyor as possible to keep it as close as possible to the discharge end of the dipper handle 36. Bearing rod 55 is operatively associated with bars 53, 54, the frame 52 and the thrust members 59, 60 by means of a pin 61, there being a similar pin connection on the other side of the con-

veyor 58. The several members described reinforce the entire gantry structure.

The conveyor 58 and boom 51 are both suspended from shaft 57 by suitable cable and reeving connections. The conveyor and boom are proportioned by weight and thrust to substantially balance each other to thereby reduce the stress on the shaft or support 57 and the gantry structure supporting the shaft 57.

Disposed on the outer or free end of the boom 51 is a shaft or rod 62 on which pulley brackets 63 and 64 are mounted having pulleys or sheaves 65 and 66 rotatably mounted thereon. A support 67 is suspended from the rod 57 by means of bars 68, 69. The sheaves 70 and 71 are rotatably mounted in the support 67. The cable 72 for vertically moving boom is dead ended on the support 67 and is then led around sheave 64, thence around sheaves 70, 71, thence around sheave 65, and over the sheave 73 rotatably mounted on rod 57 and down to the winch or drum 20 driven from the gear and clutch combination 19.

The conveyor 58 has sheave frames 74, 75 pivoted thereon from suitable brackets secured to the end of the conveyor. Sheaves 76, 77 are rotatably mounted in the frames. Suspended from the shaft or rod 57 by means of bar members 78, 79 is a frame or support 80 having sheaves 81, 82 rotatably mounted therein. The cable 83, by means of which the conveyor is vertically adjusted, is dead ended on the frame 80 on the opposite side of the machine from the cable 72. Cable 83 is led about sheave 77, thence about sheaves 81, 82, thence about sheave 76, thence about sheave 84 rotatably mounted on rod 57 to the drum 14 of the hoist driven by the clutch and gear combination 13.

The foregoing structural description shows that when the drums 14 and 20 are operated the boom 51 and conveyor 58 will have their vertical positions adjusted and that they will substantially counterbalance each other thereby balancing the machine as a whole and stabilizing the entire excavator structure by reason of the suspension of the boom and conveyor from the gantry structure.

The dipper assembly comprises a channel shaped handle member 86 and a dipper 87. The dipper 87 is provided with the usual digging teeth and the channel member has side elements or members 88 and 89 (Fig. 4) the lower edges of which are toothed or racked to engage with gears 90 and 91 on the shipper shaft 34. The crowd and retract mechanism previously described controls the movements of the dipper assembly 85. The dipper handle 86 is provided with a wear resisting liner 92 over at least a portion of its length.

The dipper assembly has a pivoted pulley support 93 mounted on the end thereof to which the frame of padlock sheave 94 is pivotally secured and in which the sheave 95 is rotatably mounted. The boom shaft 62 has two sheaves 96, 97 rotatably mounted thereon about which the cable 98 is passed. Cable 98 is dead-ended on the boom 51 and is then led over sheave 96, thence around sheave 95, thence over sheave 97 to the drum 43 of the hoist controlled by the clutch and brake elements 44 and 45. Elements 43, 44 and 45 vertically operate the dipper assembly 85 in the usual manner.

The conveyor 58 is provided with a pair of sprockets (not shown) mounted on a shaft 99

that is rotatably supported in the conveyor at one end thereof. Shaft 49 is rotatably mounted in the other end of the conveyor 58. Sprocket or gear 104 is secured to the shaft 49 for rotation therewith. The conveyor is made up of a channel member 103 reinforced by side members 102, 102. Conveyor 58 is known as a "Flight Type Conveyor" which basically comprises a double or single chain and having a plurality of lats 100, secured thereto. The chain belt or belts (not shown) pass around sprockets 101, 101 mounted on shaft 49 and also about sprockets mounted on the shaft 99. The drive for the chain belts has been set forth above. The floor of the conveyor may, if desired, be provided with one or more trap doors 105, optionally manually removable to enable the discharge of material from channel member 103 closer to the excavator. The direction of movement of the conveyor chain and lat belt is indicated by the arrows in Fig. 1. A screw conveyor may also be used and is considered to be within the purview of the invention.

A master control station 106 is provided on the excavator to regulate and control the several 25 brake and clutch elements described above. Material picked up or loosened by the dipper is discharged therefrom down the channeled handle member 86 onto the conveyor 58 to be discharged therefrom at a place remote from the machine. 30 No turning or swinging of the upper body or deck 2 is necessary. The dipper assembly is simply held in an elevated position allowing the material to slide down the handle 86 onto the conveyor 58 thereby speeding the removal and disposal of material picked up by the dipper. The idle time of the machine is reduced because the dipper can be kept adjacent the working face at all times. The only swinging of the upper body necessary is to position the dipper adjacent succeeding cuts on the working face.

When the dipper picks up more material than can readily slide down the handle onto the conveyor, the handle 86 may have a check gate 108 arranged in suitable slots in the handle. The gate 108 is moved vertically by a pivoted handle mechanism 109. This may be arranged near the operator's control station 106 previously discussed. Handle 109 is pivoted to fulcrum 107, the handle 109 being preferably manually operated by the operator. A suitable power mechanism such as piston-cylinder device or other mechanical means controllable from the operator's station 106 may be employed. The gate 108 enables the operator to regulate the flow of material onto the conveyor 58.

That which is regarded new, novel and useful and which is sought to be protected by Letters Patent of the United States is as follows:

1. In an excavator comprising a swingably mounted upper body; a boom, one end of which is pivoted to said upper body; means to vertically adjust said boom; a dipper and handle mechanism associated with said boom; means to crowd and retract said dipper; a conveyor, one end of which is pivotally mounted on said upper body receiving material discharged from said dipper through said handle; means to vertically adjust said conveyor; and means on said upper body substantially balancing the unpivoted end of said boom, said dipper against the unpivoted end of said conveyor such that the thrust due to the weights of each are opposed to each other through said means to thereby stabilize the upper body,

2. A portable excavator comprising a swingable upper body, a boom having a dipper and handle assembly thereon pivoted to said upper body; a conveyor pivotally supported on said upper body; means on said upper body jointly supporting said boom and conveyor so that said conveyor substantially counterbalances said boom and associated parts; means to actuate said boom and said conveyor; and means associated with said conveyor to selectively discharge material carried thereby at a point removed from the outer end thereof.

3. A portable excavator comprising a swingable upper body; a boom, dipper and handle assembly pivoted to said upper body; a conveyor pivotally supported on said upper body, means on said upper body jointly supporting said conveyor and boom to align said boom and conveyor and to enable said conveyor to substantially counterbalance said boom, dipper and handle assembly; and an optionally removable trap door means in said conveyor to enable material carried therein to be discharged from the conveyor before being carried to the end of the conveyor.

4. In a self-propelled material handling mechanism; a chassis; an upper body rotatably mounted on said chassis; a boom assembly pivoted at one end thereof to said upper body; a conveyor pivoted at one end thereof on said upper body; a gantry device one end of which is secured on said upper body; and means operatively associating the unpivoted ends of said boom assembly and said conveyor with the other end of said gantry so that said boom assembly and conveyor substantially balance each other.

5. In a self-propelled material handling device; a chassis; an upper body rotatably mounted on said chassis; a boom assembly having one end pivoted to said upper body; a conveyor having one end pivoted on said upper body and aligned with said boom assembly; a gantry device one end of which is secured on said upper body; and means to adjust the elevation of said boom assembly and conveyor including cable connecting the unpivoted ends of said boom assembly and said conveyor with the other end of said gantry and enabling them to substantially counterbalance each other.

6. In a self-propelled material handling device; a chassis; an upper body rotatably mounted on said chassis; a boom assembly having one end thereof pivoted to said upper body; a conveyor assembly having one end pivoted on said upper body; a gantry mechanism one end of which is secured on said upper body; means to alter the vertical position of said boom and conveyor assemblies; and cable means connected between said means and the unpivoted ends of said boom and conveyor assemblies and operatively associated with the other end of said gantry, said boom and conveyor assemblies substantially balancing each other through the upper end of said gantry.

7. In a self-propelled material handling device; a chassis; an upper body rotatably supported on said chassis; a gantry device one end of which is secured on said upper body; a boom assembly having one end pivoted to said upper body; a conveyor having one end pivotally supported on said upper body; an individual hoisting mechanism for said boom assembly and for said conveyor; sheave means associated with the other end of said gantry device; and cable means connected between each hoisting mechanism and the unpivoted end of said boom assembly and the un-

pivoted end of said conveyor and operatively associated with said sheave means in order to alter the vertical position of each while substantially balancing each other in order to stabilize said chassis and upper body.

8. In a self-propelled material handling device; a chassis; an upper body rotatably mounted on said chassis; a gantry device supported on said upper body and having sheave means thereon; a boom and dipper assembly having one end thereof pivoted to said upper body; a conveyor having one end thereof pivoted with respect to said upper body on said gantry device; a pair hoisting mechanisms on said upper body; cable means connecting each of said mechanisms and the free ends of said boom assembly and said conveyor and operatively associated with said sheave means to alter the vertical position of each pivoted member; said dipper pivoted to said boom and adapted to discharge material onto said conveyor; and said gantry device supporting the free ends of said boom and conveyor so that said upper body is substantially stabilized.

9. An excavator comprising a chassis having an upper body rotatably supported thereon; a boom; means to pivotally support one end of said boom on said upper body and whose other end is unpivoted; a dipper consisting of a scoop and a channeled handle and operatively associated with said boom; a conveyor; means to pivotally support one end of said conveyor on said upper body and whose other end is unpivoted; means on said upper body to support the unpivoted ends of said boom and said conveyor so that said conveyor and said boom substantially counterbalance each other; means to actuate said dipper; and means to actuate said conveyor so that material discharged thereon from said scoop through said handle may be conveyed to a point remote from the excavator working face without rotating said upper body.

10. An excavator comprising a chassis having an upper body rotatably mounted thereon; a boom, one end of which is pivoted to said upper body and whose other end is unpivoted; a support on said upper body; means to suspend the unpivoted end of said boom from said support and which includes means to adjust the vertical position of said boom; a dipper to remove material from an excavator working face which consists of a scoop and a channeled handle; means to actuate said dipper; a conveyor, one end of which is pivotally supported on said upper body and whose other end is unpivoted, said conveyor lying in substantially the same vertical plane as said boom and dipper; means to suspend the unpivoted end of said conveyor from said support which includes means to adjust the vertical position of said conveyor, said conveyor counterbalancing said boom and dipper through said support to thereby stabilize said upper body; and means to actuate said conveyor so that material discharged thereon from said scoop through said handle may be removed to a point remote from said excavator working face.

11. An excavator comprising a chassis having an upper body rotatably mounted thereon; a boom, one end of which is pivoted to said upper body and whose other end is unpivoted; a dipper to remove material from an excavator working face and consisting of a scoop and a channeled handle operatively associated with said boom; a conveyor, one end of which is pivotally supported on said upper body and whose other end

is unpivoted; means on said upper body to support the unpivoted ends of said boom and said conveyor so that they substantially counterbalance each other through said means to thereby stabilize said upper body; and means to operate said conveyor so that it may convey material discharged thereon from said scoop through said handle to a place remote from the excavator working face without rotating said upper body.

12. An excavator comprising a chassis having an upper body swingably mounted thereon; a boom, one end of which is pivoted to said upper body and whose other end is unpivoted; a dipper to remove material from an excavator working face and having a channeled handle connected thereto and operatively associated with said boom; a conveyor, one end of which is pivotally supported on said upper body and whose other end is unpivoted; means on said upper body from which to suspend the unpivoted ends of said boom and said conveyor so that they counterbalance each other through said means to thereby stabilize said upper body; means to adjust the vertical position of said boom; and means to actuate said conveyor so that material discharged thereon from said dipper through said handle may be conveyed to a place remote from the excavator working face without swinging the upper body on said chassis.

13. An excavator comprising a chassis and having an upper body swingably supported thereon; a boom, one end of which is pivoted to said upper body and whose other end is unpivoted; a dipper to remove material from an excavator working face consisting of a scoop and a channeled handle operatively associated with said boom; a conveyor, one end of which is pivotally supported with respect to said upper body and whose other end is unpivoted; means on said upper body from which to suspend the unpivoted ends of said boom and said conveyor so that they counterbalance each other through said means to thereby stabilize said upper body and when it is swung; means to change the vertical position of said conveyor; and means to operate said conveyor so that it may convey material discharged thereon from said dipper through said handle to a place remote from the excavator working place without swinging said upper body.

14. An excavator comprising a chassis; an upper body rotatably supported thereon; a boom, one end of which is pivoted to said upper body and whose other end is unpivoted; a conveyor, one end of which is pivotally supported on said upper body and whose other end is unpivoted; and means on said upper body from which to suspend the unpivoted ends of said boom and said conveyor so that they counterbalance each other through said means.

15. An excavator comprising a chassis; an upper body swingably supported thereon; a boom on said upper body; a conveyor on said upper body; and means on said upper body to support each end of said boom and said conveyor so that they counterbalance each other through said means to thereby stabilize said body during operation of the excavator and whenever said upper body is swung on said chassis.

16. An excavator comprising a chassis; an upper body rotatably mounted thereon; a boom, one end of which is pivoted to said upper body and whose other end is unpivoted; a conveyor, one end of which is pivotally supported on said upper body and whose other end is unpivoted; means

on said upper body from which to suspend the unpivoted ends of said boom and said conveyor; to thereby enable said upper body to be stabilized; means to change the vertical position of the unpivoted end of said boom; means to change the vertical position of the unpivoted end of said conveyor; and means on said first mentioned means about which each of the two last mentioned means operate to enable said boom and said conveyor to be vertically adjusted independently of each other.

17. An excavator comprising a chassis; an upper body rotatably mounted thereon; a boom, one end of which is pivoted to said upper body and whose other end is unpivoted; a dipper operatively associated with said boom; a conveyor assembly, one end of which is pivotally supported on said upper body and whose other end is unpivoted; and lateral thrust absorbing means mounted on said upper body from which the unpivoted ends of said boom and said conveyor are suspended in a manner to enable the lateral thrust of said boom and associated dipper and of said conveyor to be placed in substantial opposition to each other to thereby stabilize said upper body.

18. In a device as defined in claim 17 which includes means to adjust the vertical position of said boom without changing the vertical position of said conveyor.

19. In a device as defined in claim 17 which includes means to change the vertical position of said conveyor without changing the vertical position of said boom and its associated dipper.

20. In an excavator, a chassis; an upper body swingably mounted on said chassis; a boom, one end of which is pivotally associated with said upper body and having a dipper and handle mechanism; a conveyor, one end of which is pivotally associated with said upper body and that receives material from said dipper through said handle; means on said upper body associating the unpivoted end of said boom and its associated dipper and handle mechanism with the unpivoted end of said conveyor so that the devices substantially counterbalance each other; and means to change the vertical position of said boom and said conveyor.
